PAGE 2

FIGURE 1 is a front elevational view of a lathe bed, showing my new design.

FIGURE 2 is a top plan view thereof.

FIGURE 3 is an elevational view taken from the left side thereof.

FIGURE 4 is an elevational view taken from the right side thereof.

FIGURE 5 is a perspective view taken from the top and rear thereof.

FIGURE 6 is a sectional view taken substantially on line 6-6 of FIGURE 5.

FIGURE 7 is a bottom perspective view.

FIGURE 8 is a sectional view taken substantially on line 8-8 of FIGURE 2.

The broken line showing of the headstock, tool carriage, and tailstock in FIGURE 1 is for purposes of illustration only.

I claim:

The ornamental design for a lathe bed, substantially as shown and described.
